UNITED STATES PATENT OFFICE.

RALPH W. HUTCHENS, OF EAU CLAIRE, WISCONSIN.

DESIGN FOR A TIRE-TREAD OR SIMILAR ARTICLE.

58,756.

Specification for Design.

Patented Aug. 30, 1921.

Application filed April 1, 1921. Serial No. 457,828. Term of patent 14 years.

To all whom it may concern:

Be it known that I, RALPH W. HUTCHENS, a citizen of the United States, and residing in the city of Eau Claire, county of Eau Claire, and State of Wisconsin, have invented a new, original, and ornamental Design for a Tire-Tread or Similar Article, of which the following is the specification, reference being had to the accompanying drawings, forming a part thereof.

In the drawings:

Figure 1 is a plan view of a tire tread having substantially octagonal integral pro-

jections arranged in transverse rows, the projections of each row being connected by relatively narrow integral connecting portions.

Fig. 2 is a sectional view taken on line 2—2 of Fig. 1.

I claim:

The ornamental design for a tire tread or similar article as shown and described.

RALPH W. HUTCHENS.
